UNITED STATES PATENT OFFICE.

GEORGE N. MASON, OF READING, PENNSYLVANIA, ASSIGNOR TO READING HARDWARE COMPANY, OF READING, PENNSYLVANIA, A CORPORATION OF PENNSYLVANIA.

REVERSIBLE LOCKING-BOLT.

1,019,678.

Specification of Letters Patent.

Patented Mar. 5, 1912.

Application filed January 11, 1912. Serial No. 670,557.

To all whom it may concern:

Be it known that I, GEORGE N. MASON, citizen of the United States, residing at Reading, in the county of Berks and State 5 of Pennsylvania, have invented certain new and useful Improvements in Reversible Locking-Bolts, of which the following is a specification.

This invention relates to improvements in 10 locking bolts and the object in the present instance is to provide a bolt of the class illustrated, that is, one in which two bolts are simultaneously moved in opposite directions, with means for reversing the action 15 of the handle, so that the lock may be applied in either right or left hand position.

The principal feature of this device is the simple means for converting the lock from right to left hand, or vice versa.

20 The invention consists, in addition to the usual casing, movable bolts and operating handle, of a pair of rings one of which serves as the means through which the handle moves the bolts and the other a reversible stop ring, capable of being placed in position in the casing in such manner that the bolt moving ring will be operable in either the right or left hand action. The only change necessary to convert the lock 25 from one to the other handle movement is the reversal of this stop ring, all other parts remaining in the same position.

The invention is more fully described in the following specification and clearly illustrated in the accompanying drawing, in which:—

Figure 1 is a plan view, with the back plate removed, showing the bolts in retracted position and set for left hand action. Fig. 40 2 is a like view with the bolts in projected position, the handle having been moved the entire distance, as indicated by the arrows. Fig. 3 is a central sectional view on line 3—3 of Fig. 2. Fig. 4 is a view of the 45 side of the casing with all the parts removed. Fig. 5 is a like view with the stop ring in position therein, for right hand action. Fig. 6 shows the stop ring in detail and Fig. 7 shows the bolt moving ring in 50 detail.

The numeral 1 designates the casing and 2 the locking bolts. These bolts are identical in construction, and each is formed at its inner end with a reduced portion 3, al-

lowing the ends to lap over each other when 55 moved. These ends are each formed with a lateral groove 4 on the under face and with a semi-circular depression 5 on the inner face of the reduced portion. A lug 6 is also formed on the outer face, near the extremity, 60 which serves as a guide and which contacts with the inner wall of the casing when the bolts are moved.

Immediately beneath the bolt ends is centrally mounted a bolt moving ring 7, which 65 is secured by any suitable means to the operating handle 18 which enters through an opening 8 in the casing and this ring is formed with two diametrically opposite lugs 9, adapted to engage the bolts in the lateral 70 grooves 4, so that when the ring is turned by the movement of the handle, the bolts will be projected and retracted. The depressions 5 in the bolt ends are intended for clearance, so that when the bolts are re- 75 tracted as shown in Fig. 1, the lugs 9 will not interfere with the full retraction of the bolts. This bolt moving ring is formed with a peripheral projection 10, located beneath one of the lugs 9 which is adapted to engage 80 a stop to limit the movement of the ring and bolts. The casing is formed with an annular internal ridge 11, surrounding the handle opening and this ridge is formed with two pairs of oppositely disposed 85 slots 12.

The numeral 13 designates the stop ring. This ring fits loosely inside of the ridge 11 and it is formed with two peripheral projections 14, which, while at approximately 90 diametrically opposite points, are both on the same side of the imaginary vertical center of the ring, so that when placed in position in the ridge, the stops will enter the slots 12 on the same side of the center. 95 These stops project beyond the outer edge of the ridge and lie normally in line of the projection 10 on the under face of the bolt moving ring, so that, when the handle is turned carrying with it the bolt moving 100 ring, its movement will be limited by contact with these stops. It is evident therefore, that with the parts assembled as shown in Fig. 2, the handle is free to move only as a left hand device, while with the stop ring 105 13 in reversed position, as shown in Fig. 5, the handle would be free to move only as a right hand device. By means of reversing

the position of this stop ring in the casing, the device is easily converted from one to the other form of lock action.

Having thus fully described my invention, what I claim and desire to secure by Letters Patent is:—

1. In a locking bolt a casing, a pair of bolts, a rotating member, an operating handle, said rotating member having a pair of bolt engaging lugs and a peripheral projection and a reversible stop ring having radial projections thereon, in combination with a slotted ridge in the casing adapted to so hold said ring as to determine the direction of movement of the operating handle.
2. In a locking bolt a casing, a pair of bolts, means for operating the bolts in unison, a slotted ridge formed in the casing, a reversible stop ring adapted to fit in said slotted ridge so as to determine the direction of movement of the operating means and stops on said ring to limit the movement of the operating means.
3. In a reversible locking bolt comprising a casing, a pair of oppositely movable

bolts and means for operating the bolts in unison, the combination therewith of a reversible, annular member formed with peripheral projections and a slotted ridge in the casing adapted to so receive the annular member as to determine the direction of movement of the operating means.

4. In a locking bolt, a casing, a pair of bolts, each of which is formed with a reduced inner end, a rotating member, an operating handle to which said member is secured, said member having a pair of bolt engaging lugs and a peripheral projection, a slotted ridge in the casing, and a reversible stop ring adapted to fit in said slotted ridge so as to determine the direction of movement of the handle, and stops on said ring to limit the movement of said rotating member.

In testimony whereof I affix my signature in presence of two witnesses.

GEORGE N. MASON.
